Robert S. Bolger

UNITED STATES PATENT OFFICE.

ROBERT S. BOLGER, OF NEW YORK, N. Y.

LAMINATED ARTICLE.

Application filed August 6, 1925. Serial No. 48,641.

The invention described in this application is an improvement on the inventions patented by me in Patent Number 1,366,336 granted Jan. 18, 1921, and in Patent Number 5 1,445,931 granted Feb. 20th, 1923, and appertains to certain modifications and advances thereon.

In Patent 1,366,336 is described a method of forming spools and the like from a specially formed blank, by spirally or straight winding the blank on itself. In Patent 1,445,931 is described a method of forming spools and the like wherein a tube is first formed in a manner well known in the art 10 and the tube so formed is excised to give the desired shape. The advantages of helically wound tubes in such a process is therein explained.

Both of the processes described in the 20 patents mentioned above have certain practical and manufacturing difficulties and economic disadvantages. The spirally wound tube using the above mentioned blank has the disadvantage that the blank must be wound 25 that is straight wound about a mandrel of relatively small diameter in order to build up a tube body of sufficient thickness, and of required outside diameter and also have the required inner diameter, usually relatively small, which are required of spools, 30 cops, etc. This is a troublesome and difficult operation. It is discontinuous. Another difficulty lies in the slowness of the process. Spiral winding is very slow compared to helical winding. Since the surface 35 of the spools or cops, etc., must be buffed and smoothed the paper when employed must be of relatively high grade in order that it may be so smoothed and polished. It is only the layers near the surface that 40 must of necessity be of such fineness for the purpose of polishing. This process of spiral wound spools thus entails the use of a relatively high grade paper in the body of the 45 spools. This is an economic waste.

This method of the Patent 1,445,931 has 50 also certain disadvantages. First a helically wound that is continually wound tube when formed into a spool will have its end flanges, which are relatively thin at the top, helically wound. This gives a very weak formation and the flanges tend to fray and unravel. This is also true of the barrel portion of the spool, cop etc. Another 55 disadvantage identical with the last named disadvantage in the spiral wound spool or cop

formed in the method of either of the 60 patents mentioned above is that the high grade paper required for the surface finishing must be used in the body of the spool.

It is with the view of employing the 65 advantages of the methods described in the above mentioned patents and to avoid the above mentioned difficulties and disadvantages that I have invented the process to be 70 described below:—

The new process is broadly to wind a tube 75 helically of the desired thickness and diameter and winding on the helical tube as a mandrel a second tube in spiral formation; 80 This composite tube may then be excised to the desired form. As a modification the blank which is to be wound spirally may first be prepared by cutting out certain portions so that the article may be in the rough 85 shape when the blank is spirally wound on the helically wound tube.

Among the valuable features of this 90 process are that I employ the advantages of speed and ease of winding on small diameter 95 mandrels that is inherent in the helical winding together with the strength that the spiral winding gives to the article. I may also employ because of this method a cheap stock for forming the helically wound tube 100 and the better grade required for the surface in winding the spiral portion.

It is an object of my invention to excise 105 a composite wound tube to form articles of desired shape, such as spools, cops or other shapes which may be formed by shaping or excising such tubes.

It is a further object of my invention to 110 form a specially shaped tube by first helically winding a tube and there-upon spirally 115 winding a specially cut out blank of desired shape, size and material.

It is a further object of my invention to 120 form approximately tubular articles or articles formed from tubular shapes wherein 125 the core is helically wound and the outer laminæ are spirally wound.

It is a further and more specific object of my invention to form spools, bobbins 130 or cops or such articles by the methods above described and hereinafter to be more 135 fully described wherein the core is helically wound and the outer laminæ of the body and flange portions are spirally wound.

It is a further object of my invention to 140 form a composite wound tube of two different types of winding specifically helical and

spiral and particularly of a helically wound core and spiral wound outer layers.

The description will be more fully understood by reference to the attached drawings 5 of which:

Fig. 1. is a helically wound tube of desired length, thickness and diameter such as is adapted to form the inner core.

Fig. 2. is an end view of Fig. 1.

10 Fig. 3. is a view of a specially cut out blank adapted to be spirally wound on the tube of Fig. 1 to give a tube of such shape as to give a plurality of desired shapes.

Fig. 4. is a section on line 4—4 of Fig. 3.

15 Fig. 5. is a view in perspective showing the helically wound core and the prepared adhesively coated blank to be wound spirally thereon.

Fig. 6. shows the completely wound tube 20 resulting from the winding operation of Fig. 5, i. e. having a helically or continuously wound core and spirally or straight wound outer laminae and flange portions.

Fig. 7. is a section on line 7—7 of Fig. 6.

25 Fig. 8. shows the finished spools.

Fig. 9. shows a modification wherein a noncut-out blank is wound spirally on a helically wound core.

Fig. 10. is a phantom view of the 30 completely wound tube showing the helically wound core, i. e. the core being continuously wound and spirally wound, i. e. straight wound outer laminae and flange portions.

Fig. 11. is an end view of the tube illus- 35 trated in Fig. 10.

Fig. 12. is the tube undergoing the final excising and grinding operations.

Fig. 13. is the ground and severed spools. 40 The figures are largely self explanatory in view of the aforesaid explanations and discussion. The core is wound helically around a mandrel of desired diameter so as to give the central opening which may be desired. Sufficient number of plies are 45 wound so as to give the desired thickness. The tube as formed moves off the mandrel laterally. This winding operation is old and well known in the art. As the tube is formed and as soon as it reaches the desired 50 length it is severed.

The tube must be of sufficient length to be able to act effectively as a mandrel for the next winding operation. It must also be of sufficient length so that the tube after the 55 second winding operation shall be of desired length to give either the shape or the number of shapes required.

The next winding operation consists of 60 winding a blank of required length around the aforesaid tube in a spiral formation. When the blank illustrated in Fig. 3 is used it is first cut out in desired shape before it is wound. In making spools the blank may be cut out in a plurality of trapezoidal shapes.

The barrel forming portion 1 of the blank should be at least greater than one circumference of the body of the spool. Preferably the length should be sufficient to give several laminae of spirally wound blank. The 70 length of the flange forming portions 2 of the blank should be sufficient to give the height of the flange portion of the spool which may be desired. The slope of the sides of the cut out trapezoids should be 75 such as to give the desired slope to the flanges of the spools. Portion 3 of the trapezoids should be of such length as to give the desired length of barrel for the spool. The tabs 4 should be of such width 80 as to hold the blank together during the winding operation. Were this tab to be dispensed with as it may, it would increase the difficulties in the winding operation since the flange portions will not have anything to hold them in alignment. As pointed out above one of the tabs should be long enough to give several laminae, at least 85 more than one circumference of the spool body. This tab is first wound on the helical tube when the blank is wound spirally 90 around the helically wound tube.

While Fig. 5 shows a blank for forming a three spool tube it is obvious that any 95 number may be formed depending on the size of the tube illustrated in Fig. 1 and 5 and the size of the blank and number of cut outs in Fig. 3 and 5.

When the winding operation is completed 100 the shape shown in Fig. 6 results.

The next steps are the grinding and finishing steps. There is very little grinding to do. The tabs are first cut away and the grinding tool smooths the rough parts off.

The next step is that in which the tube 105 is severed to give the finished spool as shown in Fig. 8.

When the method illustrated in Fig. 9 is employed, a helically wound core of desired length to give a practical size mandrel and 110 also of desired length from which the shape or shapes may be formed, is wound in the manner and fashion described above and a blank of the length and width sufficient to give the tube of required length and thick- 115 ness is spirally wound upon the helically wound core which acts as a mandrel. The shape 10 is then formed. The length of the blank in Fig. 9 must be sufficient to give the thickness of the tube in Fig. 10 when it is 120 wound on the core in Fig. 9. Usually the core makes up the major thickness and the blank, to be wound spirally, must be of sufficient length to build up the end flanges in the case of the spool and also allow for at 125 least one and usually more than one laminae for the body portion. This limits the amount of the better grade of paper that must be used in the outer blank to form the outer part of all of the articles to be formed 130

and allows for grinding and polishing purposes. In other words the blank should be of sufficient length to form both the major and minor diameter of the article to be formed.

5 Thus when the article is a spool all of the surfaces contacting with the contents wound thereon is of the better grade of material.

The tube thus formed may be of any desired length conditioned by the practicable size of the spiral wind and the helical wind and the use of the helical wound core as a mandrel. The number of shapes to be formed therefrom depends on the character and size of the shapes and on the size of the tube.

10 The tube may be ground in any desired manner as illustrated in Fig. 12 to form the shapes specifically shown as spools. Fig. 13 shows the final shape or spools severed from the tube upon which a plurality of shapes were simultaneously formed.

15 While any material suitable for the winding of grinding operations here illustrated such as paper, veneer, fabrics or other sheet material may be employed, I prefer to use paper both because of its price and availability and also because of its workability. It is understood that any type of adhesive or means for cementing together the several laminae of the tube or tubes may be used, but other means of holding the parts together may be used, such as bands, either alone or in addition to the adhesive material.

20 I prefer to use adhesive in forming the tubes and to use the bands additionally when this proves advisable.

25 While I have thus specifically described my invention in accordance with law I do not desire the same to be taken as limiting the invention but only illustrative of the invention which I claim is:—

30 1. The method of forming laminated articles having more than one external diameter which comprises helically winding a tube of sheet material to form a tube of an external diameter not greater than a minor diameter of the said article and spirally winding on said helically wound tube a blank of sheet material, the thickness of said spiral winding being at least sufficient to form on said helically wound tube the maximum external diameter of said article.

35 2. The method of forming laminated articles having more than one external diameter which comprises helically winding a core of a diameter less than a minor diameter of the article to be formed and spirally winding on said core outer layers of a thickness to form at least the maximum diameter of said article.

40 3. The method of forming laminated articles which comprises forming a composite wound tube by helically winding a tube of

sheet material to form a tube of desired shape and size and spirally winding on said helically wound tube as a mandrel a blank of sheet material and grinding said composite wound tube to desired shape.

4. The method of forming laminated articles which comprises helically winding a tube of sheet material to desired size, spirally winding on said helically wound tube as a mandrel a blank of sheet material to give a composite wound tube and excising said composite wound tube to form a desired shape.

5. The method of making laminated spools which comprises helically winding a tube of sheet material to give a helically wound tube of desired shape and spirally winding on said helically wound tube as a mandrel a blank of sheet material to give a composite tube of desired size and excising said latter tube to give a plurality of spool shapes and severing said shapes to give individual spools.

6. The method as described in claim 5 in which the sheet material employed is paper of desired grade.

7. The method of forming laminated articles which comprises helically winding a tube of sheet material to give a tube of desired size, forming a blank of sheet material by cutting out portions thereof in order to give approximately the desired shape when the blank is spirally wound on said helically wound tube as a mandrel, winding said blank on said helically wound tube to give a plural wound tube-like shape comprising an inner helically wound core and outer laminae spirally wound.

8. In the method defined in claim 7, grinding said plural wound tube-like shape to form a smooth tube-like shape of the desired fashion.

9. The process of forming laminated spools which comprises helically winding a tube of sheet material about a mandrel of a size to give the desired central opening of the spool and continuing the winding operation until a tube of desired length at least equal to the sum of the lengths of spools to be formed therefrom and diameter is formed, severing the tube as it comes off the mandrel, forming a blank of a width approximately equal to the length of the aforementioned tube and of a length sufficient to give the maximum diameter of the spool when the blank is wound on said helically wound tube, cutting out of said blank a number of trapezoids equal to the number of the spools to be formed from said blank, the minimum width of the trapezoids being equal to the length of the barrel portion of said spool and the slope and perpendicular height of the sides of said trapezoidal cut-outs being such as to give the desired height and slope to end the portions of the spools

formed, said trapezoidal cut-outs being so formed as to be entirely within the edge portions of the blank so as to form connecting tabs between said trapezoids, the width 5 of one of said tabs being greater than one outer circumference of the spools, spirally winding said blank on said helically wound tube as a mandrel in such manner that the last mentioned tab is first wound thereon 10 thus forming a plurality of spool shapes equal to the number of trapezoidal cut-outs, grinding said shapes to desired thickness and smoothness and then severing said spool shapes to give individual finished laminated 15 spools having an inner helically wound core, outer layers spirally wound and spirally wound end flanges.

10. In the method as defined in claim 9, in which the material used is paper of desired quality.

11. A laminated spool comprising a helically wound core and spirally wound end flanges.

12. A laminated paper spool comprising 25 a helically wound core and the outer laminae of the barrel portion of the spool spirally wound and spirally wound end flanges.

13. The method of forming laminated articles having more than one external diameter which comprises helically winding 30 a tube to a diameter less than a minor ex-

ternal diameter of the article to be formed and spirally winding on said helically wound tube as a mandrel a blank of sheet material to build up on said helically wound tube a thickness to form at least the maximum external diameter of the article to be formed and excising said tube to the desired shape.

14. The method of forming laminated articles having more than one external diameter which comprises helically winding a tube to a diameter less than a minor external diameter of the article to be formed 45 and spirally winding on said helically wound tube as a mandrel a blank of sheet material to build up on said helically wound tube a thickness to form at least the maximum external diameter of the article to be 50 formed and excising said tube to give a plurality of spool shapes and severing said shapes to form individual spools.

15. The method of forming laminated spools which comprises helically winding a tube of sheet material to thickness less than the diameter of the barrel of the spool, spirally winding on said helically wound tube, sheet material to form at least the maximum diameter of the spool and excising 55 said tube to the desired spool shapes.

In testimony whereof I affix my signature.

ROBERT S. BOLGER.
